ARRANGEMENT FOR IMPROVING OPERATION OF HYDRAULIC TURBINE

Paul D. Hess, Brookfield, Wis., assignor to Allis-Chalmers Manufacturing Company, Milwaukee, Wis.

Application July 22, 1957, Serial No. 673,415

7 Claims. (Cl. 253—117)

This invention relates to hydraulic turbines and more particularly to an arrangement for admitting air below the runner to improve the operation of the turbine.

A hydraulic turbine is designed so its efficiency is best at full load. At part loads there are occasions when the water stream causes voids to be formed below the runner. This results in noise and rough operation.

One way of controlling the noise and rough operation is to admit air into the area where the voids are formed. Air can be introduced into the water stream through ports provided in a hollow cap attached to the end of the runner. This is well known. See, for example, U.S. Patent 2,079,258 to Kerr.

Normally, vacuum created by the water stream moving by the hollow cap draws air through ports in the cap into the area subject to the voids. The source of air can be the atmosphere. This is also well known.

There is a disadvantage in relying on vacuum per se to draw the air through the ports in the cap. The vacuum may be weak and cannot draw in enough air to be effective. Also under conditions of high tail water, there may be a slight back pressure in the area around the cap of the runner sufficient to counteract atmospheric pressure and the effect of the water stream moving by the cap of the runner tending to draw air out through the ports. A slight back pressure will not however eliminate voids, it merely makes more difficult the problem of getting air to the location of a void and a pressure greater than atmospheric will be required to move the air from the ports to such locations.

Essentially, my invention involves connecting a series of vanes to a part of the turbine that rotates. The rotating part will rotate the vanes. The vanes will act as a compressor, forcing air through the interior of the hollow cap at the end of the runner and out ports in the side of said cap.

My invention also involves providing openings in said vanes. Fluid can flow through the openings in the vanes to unblocked ports if a port, or ports, becomes blocked. This way fluid cannot be trapped between vanes. Also, the vanes continue to function, in that they can supply fluid to unblocked ports.

It is an object of my invention to provide an improved arrangement that introduces a larger amount of air into the water stream than has previously been possible, and which also introduces air into the water stream under conditions when this could not be done previously.

It is another object of my invention to provide an improved cap containing vanes, whereby the vanes will continue to function if some of the ports in the cap become blocked.

It is another object of my invention to provide an improved cap containing vanes, that can be easily attached to and disconnected from the runner to facilitate maintenance or substitution of caps.

Other objects and advantages will appear from the

2

following description considered in conjunction with the attached drawing, in which:

Fig. 1 is a sectional view of a hydraulic turbine showing the hollow cap connected to the runner; and

Fig. 2 is a plan view of the hollow cap taken in the direction of arrows II—II of Fig. 1.

Referring to Fig. 1 there is disclosed a portion of a hydraulic turbine 2 in this instance, a Francis turbine. Broadly, turbine 2 comprises: head cover 4 that is stationary and serves as a support for rotating element 6 which carries blades 8, a spiral casing 10 (only a portion being shown) through which the water stream flows to blades 8, and a series of wicket gates 12 that control the flow of the water stream from spiral casing 10 to blades 8. After passing through the blades the water stream exits through a draft tube 14.

Rotating element 6 comprises: shaft 16, runner 18, and cap 20. Shaft 16 is connected at one end to a generator (not shown). The other end of shaft 16 is provided with coupling flange 22. Coupling flange 22 is connected by bolts 24 to runner 18 which carries blades 8. Cap 20 is connected to the under surface of runner 18. Cap 20 guides the water as it leaves blades 8.

Cap 20 is hollow and cone shaped. The cap is made up of cone portion 26, cylindrical portion 28 connected to the large diameter end of the cone portion, and flange portion 30 supported by cylindrical portion 28. Flange portion 30 is normal to, and faces the axis of cone portion 26. Flange portion 30 is removably secured by bolts 32 to runner 18.

Although other connecting means can be used, the cone portion, cylindrical portion and flange portion are secured together by welding.

The bottom of cone portion 26 is closed by cover plate 34. Cover plate 34 is removably connected by bolts 36 to plate 38 fastened to the interior of the small diameter end of cone portion 26. Plate 38 has an opening 40 in its center for entrance to the interior of the cap, and for access to bolts 32 that connect flange portion 30 to runner 18.

Attachment as well as maintenance of cap 20 is easy. All that is necessary is that cover plate 34 be removed for access to the interior of cap 20.

Connected to the inside surface of the cap are a plurality of vanes 42. Vanes 42 have a bottom portion 44, and a top portion 46 positioned obliquely above and outwardly of said bottom portion. Bottom portion 44 abuts plate 38, and top portion 46 abuts flange portion 30.

Any connecting means can be employed to connect vanes 42 to cap 20. In the embodiment disclosed, the edge of vanes 42 are welded to the cap.

As can be seen in Fig. 2, vanes 42 extend toward the axis of the rotating element and form a fan member. Ports 48 (Fig. 1) are located in cone portion 26 intermediate top and bottom portions 44, 46 of said vanes. There is a port provided between adjacent vanes.

Although only a single port (Fig. 2) is illustrated between adjacent vanes, obviously additional ports can be provided. Also, although the vanes are illustrated as straight (Fig. 2), the vanes can be curved to provide a larger vane surface. It is further noted that vanes 42 have the additional function of strengthening the cap, since they will also act as reinforcing members.

Occasionally a port, or ports, may become clogged by foreign matter. In that event, vanes 42 directing fluid to those ports would become useless.

In addition, when rotating element 6 is not rotating, water flows back through ports 48 in cap 20 flooding head cover 4. Normally, when rotating element 6 starts rotating, the water flows back out ports 48. However, if some ports 48 are blocked, water can be trapped be-

tween two adjacent vanes (Fig. 2) and slightly unbalance runner 18.

To prevent water from being trapped between the vanes, or the vanes from not functioning, openings 50 are provided in the edge of each vane connected to the inside surface of cone portion 26. Openings 50 permit fluid, which can be air or water, to flow from ports 48 which may be clogged to other ports 48 that are open. In this way, the vanes continue to operate if some ports are blocked.

Ports 48 in cap 20 are connected by passage means to a source of air (not shown) outside the runner. The passage means comprises: the interior of cap 20 which contains vanes 42, axial passage 52 in shaft 16, radial passages 54, and passages 56 in head cover 4. It is noted that vanes 42 are in the passage means.

Air from the source passes through passages 56 in the head cover 4, radial passages 54, axial passage 52, the interior of the cap 20, and out ports 48.

Although passages 54 are illustrated as extending radially, they can be dispensed with and axial passage 52 extended the length of shaft 16 and directly connected to a source of air.

In summary:

My invention provides a new improved arrangement that utilizes vanes that are turned by the rotating element to force air into the water stream below the runner.

My invention provides a simple arrangement wherein vanes on the inside of the cap are provided with openings so they continue to function even when ports between them become blocked.

And finally, my invention provides a simple cap containing vanes, whose cover plate can be easily removed to provide access to the vanes, ports or bolts so the cap can be attached or removed from the runner to facilitate maintenance or substitution of caps.

Although but a single embodiment of the present invention has been illustrated and described, it will be apparent to one skilled in the art that various changes and modifications may be made therein without departing from the spirit of the invention or from the scope of the appended claims.

What is claimed is:

1. A hydraulic turbine comprising: a rotating element rotated by a water stream, said rotating element including a shaft and a runner connected to said shaft, a hollow cap connected to said runner, a plurality of ports in the surface of said hollow cap, passage means connecting said ports to a source of air external of said turbine, a plurality of spaced vanes in said passage means, means connecting said spaced vanes to said rotating element, said vanes rotating in response to rotation of said rotating element, said vanes on rotating drawing air from said source through said passage means and forcing said air out said ports in said cap below said runner.

2. A hydraulic turbine comprising: a rotating element rotated by a water stream, said rotating element includ-

ing a shaft and a runner connected to said shaft, a hollow cap connected to said runner, a plurality of spaced vanes, means connecting an edge of each of said vanes to the inside surface of said hollow cap, said vanes extending toward the axis of said runner and forming a fan member, said vanes having top and bottom portions, said top portions positioned obliquely above and outwardly of said bottom portions, a plurality of ports in the surface of said cap, passage means connecting said ports in said hollow cap with a source of air external of said turbine, said ports located in said cap intermediate the top and bottom portions of said vanes, said vanes when rotating drawing air from said source into said cap, and moving said air radially so it discharges out said ports.

15 3. A device as set forth in claim 2 wherein each of said vanes connected to the inside surface of said hollow cap is provided with an opening, so fluid can pass from a blocked port through said openings to an unblocked port.

4. A device as set forth in claim 3 wherein each of 20 said openings in said vanes is in the edge of said vanes that is connected to said cap.

5. In a hydraulic turbine, an improved cap for the runner of a hydraulic turbine, said cap comprising: a cone shaped portion that guides the fluid stream, a plu-

25 rality of ports in said cone shaped portion, a cylindrical portion connected to the large diameter portion of said cone portion, a flange on said cone portion normal to and facing the axis of said cone portion, means connecting said flange to said cylindrical portion, means removably

30 connecting said flange to said runner, a plate having an opening, means connecting said plate to the small diameter end of said cone portion, a cover plate, means re-

35 movably connecting said cover plate to said plate, said cover plate closing said opening in said plate, a plurality of spaced vanes, and means connecting said spaced vanes to the inner surface of said cap locating said plurality of vanes in spaced intermediate lateral relation with said plurality of ports and in intermediate relation with re-

spect to said cover plate and said flange.

40 6. A device as set forth in claim 5 wherein each of said vanes connected to the inside surface of said hollow cap is provided with an opening, so fluid can pass from a blocked port through said openings to an unblocked port.

45 7. A device as set forth in claim 6 wherein each of said openings in said vanes is in the edge of said vanes that is connected to said cap.
